UNITED STATES PATENT OFFICE.

FRANK L. SCHAEFLE, OF DUBUQUE, IOWA.

BOX-LID SUPPORT.

1,245,986.

Specification of Letters Patent.

Patented Nov. 6, 1917.

Application filed December 29, 1916. Serial No. 139,612.

To all whom it may concern:

Be it known that I, FRANK L. SCHAEFLE, a citizen of the United States, residing at Dubuque, in the county of Dubuque and

5 State of Iowa, have invented new and useful Improvements in Box-Lid Supports, of which the following is a specification.

The present invention has reference to means for supporting cigar boxes and the 10 hinged covers thereof, and designed for attachment to boxes of the above stated character for supporting the latter in show cases or like places, in such a manner as to display the merchandise contained therein.

15 A still further object of the invention resides in the production of a device of the above stated character wherein means is provided on the free terminal end of the supporting arm in order that the supporting 20 device may accommodate boxes of various sizes.

With the above and other objects in view, the invention consists in the novel features, details of construction and combination of 25 parts which will hereinafter be more fully set forth, illustrated in the accompanying drawing and pointed out in the appended claims.

Figure 1 is a side elevation of the device 30 showing the same in supporting position; and

Fig. 2 is a perspective view of the support with the box detached therefrom.

Referring more particularly to the accompanying drawing, in which like characters of reference refer to corresponding parts in the several views, 5 denotes the supporting device generally which is preferably constructed of a single strip of metal 40 or the like material and of elongated form.

The material forming this supporting member is so bent to adapt the same for receiving and supporting the box A in which the cigars are packed and shipped, and is especially useful to this extent, as from past experiences difficulties have been experienced, owing to the fragile connection of the hinged closure B to the body of the cigar box B in the handling operation of 45 the cigar box without causing the removal or damage of the cover thereof. To this end, use is made of a substantially U-shaped horizontal supporting arm 6 including a long narrow connecting portion 7, a forward vertical limb 8 and a rear straight vertical limb 9. The length of the rear

limb 9 exceeds the length of the front limb 8 and adapted upon the active position of the supporting member to be disposed vertically of the box A and contact with the rear side thereof, whereas upon the latter referred to position of the supporting member, the front limb 8 resiliently engages with the front wall of the box, thus firmly supporting the box within the U-shaped supporting arm 6, and as is obvious, the connecting portion 7 thereof is arranged in engagement with the exterior portion of the bottom of the box and transversely thereof. The previously referred to limb 8 of the supporting arm is of substantially S-shape in cross section, and is formed by curving the same inwardly and in a direction toward the opposed face of the limb 9, hence this construction will permit of the supporting arm accommodating boxes of various widths. The said rear limb 9 of the supporting arm is bent to provide a long outwardly and upwardly inclined prop 11 and the point of formation of this prop with respect to the rear limb 9, will permit of the prop, upon the open position of the cover B of the box, to support the same in an open position, thereby allowing of the merchandise contained within the cigar box 50 to be displayed when such box is placed upon or within a show case (not shown).

This specific construction of supporting device enables the salesman to easily and expeditiously obtain access to the box, due to the fact that the prop 11 will permit such party grasping the upper end thereof and lift the complete box of cigars from the show case.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are within the scope of the appended claims.

What is claimed as new is:

1. A support for boxes having a hinged 110 cover comprising a single strip of material bent to provide a U-shaped supporting arm,

said supporting arm including a resilient limb adapted to engage with the front portion of the box upon the supporting position, and a prop formed contiguous with the opposite limb of the supporting arm for supporting the closure of the box in open position.

2. As a new article of manufacture, a supporting device for cigar-boxes comprising a single strip of material bent to pro-

vide a U-shaped supporting arm, said supporting arm embodying a short forward vertical resilient limb and a long straight rear limb, and a prop formed integral with the upper end of the rear limb and bent to 15 assume an upward and outward inclined position.

In testimony whereof I affix my signature.

FRANK L. SCHAEFLE.
